UNITED STATES PATENT OFFICE.

HANS HENRIK BLACHE, OF HELLERUP, NEAR COPENHAGEN, DENMARK.

BED FOR VERTICAL INTERNAL-COMBUSTION ENGINES.

1,342,939.

Specification of Letters Patent.

Patented June 8, 1920.

Application filed April 10, 1920, Serial No. 372,950.

To all whom it may concern:

Be it known that I, HANS HENRIK BLACHE, citizen of the Kingdom of Denmark, residing at Nr 32 Sofievej, Hellerup, 5 near Copenhagen, Denmark, have invented certain new and useful Improvements in Beds for Vertical Internal-Combustion Engines, of which the following is a specification.

10 Internal combustion engines are known, for which the engine-beds are placed between the cylinders, the beds being most frequently A-shaped, so as to afford space, at bottom, for the main bearing. These 15 beds rest at bottom with feet on the cross-connections of the bottom frame, and support the cylinders, whose feet rest on the bed tops. From the feet of the cylinders, long stay bolts are carried straight down 20 through the beds and through the cross-pieces of the bottom frame, as near as possible to the main bearing, and the stay-bolts are fastened by nuts at top at the cylinder and at bottom at the lower face of the bot- 25 tom frame.

The present invention relates to a construction by which the cylinders may be relieved entirely from the transmission of the heavy piston pressure by means of the 30 stay-bolts being carried up through the cylinder covers, which are already of heavy construction, because they have to resist the large explosion pressures, while the cylinder proper has to stand this pressure only for 35 a small portion of its top part, and therefore may be of light construction as far as the entire remaining length is concerned.

On the drawing, one manner of constructing the invention is illustrated,

40 Figure 1 shows a vertical section of the cylinder and cover of an engine.

Fig. 2 shows, in top view, the cylinder cover shown in Fig. 1.

The cylinder covers E, which are shaped 45 in such a manner that they meet one another at the center lines between two cylinders, are here joined together by means of the bolts L, Fig. 2. In the plane of the joint, the long connecting bolts H are carried 50 through the covers, and the latter are there- by tightened firmly against the A-shaped beds A, which are constructed in ordinary manner, with the exception that they are here extended clear up to the bottom face of 55 the covers. The cylinder portion D is fas- tened to the bottom face of the covers by

means of a flange, and this cylinder portion will now only have to be calculated accord- 60 ing to the pressure present in the cylinder and, consequently, only the upper part thereof will need to be of heavy construc- 65 tion, while in downward direction it may be designed with constantly decreasing thick- 70 nesses of wall. On the outside of the cylin- 75 der, a loose water jacket Q may be provided, if desired.

As the stay-bolts pass from the bottom edge of the cross-piece of the bottom frame and up to the top face of the cylinder cov- 75 ers E, these stay-bolts will be of consider- 80 able length in larger engines, and as they are to be tightened at a tension exceeding the one to which they will be exposed in consequence of the piston pressure, they will be subject, during this tightening, to a con- 85 siderable elongation requiring a consider- able amount of work in tightening them. In order to avoid the necessity of doing this work, whenever it becomes necessary to re- 90 move the cover in order to inspect the en- 95 gine, each stay-bolt is fitted with an extra- nut R, Fig. 1. By means of this nut, the longer part of each stay-bolt is given the requisite tension, at the same time as the A-shaped beds become tightened to the bottom frame. This work has only to be performed once, viz., when the engine is fitted up for the first time. When the covers are being placed in position, it will then only be necessary to produce the requisite tension in the shorter portion of the stay-bolt, which passes through the cylinder cover proper, and this tension requires only a slight frac- 100 tion of the work required for tightening the entire stay-bolt.

I claim:

In a multi-cylinder internal combustion engine construction, the combination of a plurality of cylinders; a cover for each cyl- 105 inder, the covers of pairs of adjacent cyl- 100 inders joining each other at the center lines between the cylinders; fastening means con- 110 necting the covers together at their joints; A-shaped beds disposed between the individ- 115 ual cylinders and extending upward into contact with the bottom faces of the covers; stay bolts extending upward through said frames and said covers in the planes of the joints between the covers, and being thread- 120 ed both at their upper ends and intermed- 125 iate their ends in the planes of the joints between the cylinders and their covers,

lower ends of said bolts being fastened at the bottoms of the beds; nuts engaged with the intermediate threaded portions of the bolts and adapted to be securely tightened against the tops of said beds so as to tension said bolts; and additional nuts engaged with the threaded upper ends of the bolts and adapted to be tightened against the up-

per faces of the covers after the tensioning of said bolts by the tightening of the first-named nuts has been completed, whereby the covers may be removed without affecting the tension of the bolts.

In testimony whereof I affix my signature.

HANS HENRIK BLACHE.
